(57) **CLAIM**

The ornamental design for an electrical connector with shared wire harness, as shown and described.

DESCRIPTION

FIG. 1 is a front and left side perspective view of an electrical connector with shared wire harness showing our new design;

FIG. 2 is a top plan view thereof;

FIG. 3 is a bottom plan view thereof;

FIG. 4 is a right side elevation view thereof, the left side elevation view being a mirror image of FIG. 4;

FIG. 5 is a front elevation view thereof; and,

FIG. 6 is a rear elevation view thereof.

The broken line in the figure drawings is included to show the unclaimed subject matter only and forms no part of the claimed design.
